CLAIM

The ornamental design for a television adapter device with video and audio outputs, as shown and described.

DESCRIPTION

FIG. 1 is a perspective view of a television adapter device with video and audio outputs showing our new design;

FIG. 2 is a top view thereof;

FIG. 3 is a side view thereof;

FIG. 4 is a front view thereof; and,

FIG. 5 is a back view thereof.

The broken lines shown represent unclaimed subject matter and form no part of the claimed design.
